(57) **ABSTRACT**

The present invention provides a constant-current-source driving system, comprising: a power source module, a primary working load module, a secondary working load module, and a weighting controller. The primary working load module is connected to the power source module in order to be driven by electricity provided by the power source module. The secondary working load module is connected to the primary working load module and parallel-connected to a variable-impedance controller. The weighting controller is connected to a first circuit of the variable-impedance controller and to a second circuit of the secondary working load module in order to obtain a first current value of the first circuit and a second current value of the second circuit, wherein the weighting controller compares a sum of the first current value and the second current value with a preset target current value and sends a control signal to the variable-impedance controller as feedback in order for a constant current to be supplied to the primary working load module.

CONSTANT CURRENT SOURCE DRIVING SYSTEM

BACKGROUND OF THE INVENTION

1. Technical Field

The present invention relates to a circuit driving system and more particularly to a constant-current-source driving system in which circuit control is carried out to make the driving current approach a constant value.

2. Description of Related Art

A light-emitting diode (LED) lamp is a lighting device that uses one or more LEDs as the light source, wherein the one or more LEDs are typically made of semiconductors. With the advancement of LED technology, high-power and high-luminance LEDs have gradually replaced the conventional light sources.

As a low-voltage semiconductor product, LEDs will be damaged by a high-than-rated voltage and therefore cannot be driven by a standard alternating-current (AC) power source directly; an additional circuit is required to control the supply of voltage and current. This circuit includes a series of diodes and resistors and is configured to control the polarity of the output voltage and limit the output current, which operations, however, cause a loss of voltage by converting any excess voltage into heat. To address the issue of heat loss and thereby reduce the loss of voltage, it is common practice to connect a plurality of LEDs in series, but this circuit configuration gives rise to another problem: should any of the series-connected LEDs be damaged, all the LEDs in the circuit will be unable to emit light.

Moreover, an LED needs to be driven by a relatively constant current during operation. If the input current varies frequently to a moderate or large extent, not only is the luminous flux likely to fluctuate, but also the LED will be subject to optical attenuation or damage, if not a shortened service life.

BRIEF SUMMARY OF THE INVENTION

The primary objective of the present invention is to provide a constant-current-source driving system, comprising: a power source module, a primary working load module, a secondary working load module, and a weighting controller. The primary working load module is connected to the power source module in order to be driven by electricity provided by the power source module. The secondary working load module is connected to the primary working load module and parallel-connected to a variable-impedance controller. The weighting controller is connected to a first circuit of the variable-impedance controller and to a second circuit of the secondary working load module in order to obtain a first current value of the first circuit and a second current value of the second circuit, wherein the weighting controller compares a sum of the first current value and the second current value with a preset target current value and sends a control signal to the variable-impedance controller as feedback in order for a constant current to be supplied to the primary working load module.

Comparing to the conventional techniques, the present invention has the following advantages:

The present invention uses a weighting controller and a variable-impedance controller to modulate the divided voltage across a secondary load module so as to ensure that the

current flowing through the primary load module is in a constant state, lest the service life of the LED(s) driven by the system be shortened by an otherwise fluctuating voltage or current.

Furthermore, the present invention recovers and reuses the electric energy that may otherwise be lost as heat but that is intended for use by the load in the first place. Thus, in addition to preventing an undesirable temperature rise of the device to which the invention is applied, the invention saves energy by reducing the power consumption of the entire circuit of the device.

BRIEF DESCRIPTION OF THE SEVERAL VIEWS OF THE DRAWINGS

FIG. 1 is a block diagram of a constant-current-source driving system according to the present invention.

FIG. 2 is a circuit diagram of a constant-current-source driving system according to the present invention that is used as an LED driving circuit.

DETAILED DESCRIPTION OF THE INVENTION

The details and technical solution of the present invention are hereunder described with reference to accompanying drawings. For illustrative sake, the accompanying drawings are not drawn to scale. The accompanying drawings and the scale thereof are not restrictive of the present invention.

A detailed description of how to implement the present invention is given below with reference to FIG. 1, which is a block diagram of a constant-current-source driving system according to the invention.

As shown in FIG. 1, the present invention provides a constant-current-source driving system 100 that essentially includes a power source module 10A, a primary working load module 20A connected to the power source module 10A, a secondary working load module 30A connected to the primary working load module 20A, and a weighting controller 40A.

The power source module 10A, whose output is connected to the primary working load module 20A, is used to provide the electric energy required for driving the primary working load module 20A. The power source module 10A in a preferred embodiment is selected from the group consisting of a rectifier, a voltage stabilizer, a transformer, a relay, and a surge protection unit (or other circuit protection modules); the present invention, however, has no limitation in this regard.

The primary working load module 20A and the secondary working load module 30A may be any working circuits. The secondary working load module 30A is connected in series to the primary working load module 20A and is connected in parallel to a variable-impedance controller 50A.

The weighting controller 40A is connected to a first circuit 51A of the variable-impedance controller 50A in order to obtain a first current value of the first circuit 51A. The weighting controller 40A is also connected to a second circuit 31A of the secondary working load module 30A in order to obtain a second current value of the second circuit 31A. The weighting controller 40A adds the first current value and the second current value together, compares the sum with a preset target current value, and sends a control signal to the variable-impedance controller 50A as feedback, in order for the current supplied to the primary working load module 20A to be constant.

More specifically, the current values obtained from the first circuit **51A** and the second circuit **31A** allow the weighting controller **40A** to modulate the impedance value of the variable-impedance controller **50A** in real time so that, by forming a closed-loop control circuit, the current output of the first circuit **51A** and the second circuit **31A** as a whole can be rendered constant.

An embodiment of the present invention is detailed below with reference to FIG. 2, which is the circuit diagram of a constant-current-source driving system according to the invention that is used as an LED driving circuit.

As shown in FIG. 2, the LED driving circuit **200** disclosed in this embodiment includes a power source module **10B**, a primary working load module **20B**, a secondary working load module **30B**, and a weighting controller **40B**.

The power source module **10B** essentially includes a rectifier **12B** connected to mains electricity **11B** and an electromagnetic interference filter (EMI filter) **13B** connected to the rear end of the rectifier **12B**. The rectifier **12B** in a preferred embodiment is a half-wave rectifier, a full-wave rectifier, or a bridge rectifier in order to convert the mains electricity into direct-current (DC) electricity. The present invention has no limitation on the mode of implementing the rectifier **12B**. The EMI filter **13B** is provided at the rear end of the rectifier **12B** to filter out the noise in the electricity output from the rectifier **12B** and thereby achieve voltage stabilization as well as current stabilization.

The primary working load module **20B** is connected to the power source module **10B** in order to be driven by the electricity provided by the power source module **10B**. In this embodiment, the primary working load module **20B** includes a plurality of series-connected or parallel-connected load units **21B**, wherein each load unit **21B** is a light-emitting unit or light-emitting array composed of one or a plurality of LEDs. To adjust the brightness of the light-emitting units or arrays (hereinafter referred to collectively as the light source for short), the rear end of each load unit **21B** is provided with a tap **22B** not only connected to the secondary working load module **30B** but also parallel-connected to a corresponding one of the variable-impedance controllers **50B** of the secondary working load module **30B**.

The secondary working load module **30B** is connected to the primary working load module **20B** and is parallel-connected to the plural variable-impedance controllers **50B** through the taps **22B** respectively. To prevent problems associated with the generation of a reverse current in the circuits (e.g., a short circuit caused by a current flowing from one of the taps to another tap), there is a forward-biased diode **23B** between the rear end of each load unit **21B** and the secondary working load module **30B**, the objective being for the forward-biased diodes **23B** to isolate the secondary working load module **30B** and the variable-impedance controllers **50B** from the load units **21B**. The number of the variable-impedance controllers **50B** must correspond to that of the taps **22B** to enable multipath voltage control.

To control the brightness of the light source (which is determined by the number of the LEDs activated), the circuit of each tap **22B** is provided with a switch unit **24B**, and each switch unit **24B** is connected to a controller **60B** in order to be turned on or off under the control of the controller **60B**.

In this embodiment, the secondary working load module **30B** may be a micro control unit (MCU), a sensor, or a constant-voltage or constant-current driving module; the present invention has no limitation in this regard. In a preferred embodiment, the variable-impedance controllers **50B** are field-effect transistor (FET)-based voltage control

resistors, whose resistance values are determined by their respective input voltage values.

The weighting controller **40B** is connected to a first circuit **51B** of each variable-impedance controller **50B** in order to obtain a first current value of each first circuit **51B**. The weighting controller **40B** is also connected to a second circuit **31B** of the secondary working load module **30B** in order to obtain a second current value of the second circuit **31B**. By comparing the sum of the first current values and the second current value with a preset target current value and sending a control signal to each variable-impedance controller **50B** as feedback, the weighting controller **40B** ensures that a constant current is supplied to the primary working load module **20B**.

More specifically, the weighting controller **40B** includes a controller **41B** connected to the variable-impedance controllers **50B** and a weighter **42B** connected to the first circuits **51B** of the variable-impedance controllers **50B** and the second circuit **31B** of the secondary working load module **30B**. To obtain the first current value of each first circuit **51B** and the second current value of the second circuit **31B**, the first circuit **51B** of each variable-impedance controller **50B** is provided with a first current sensor **52B** for sensing the corresponding first current, and the second circuit **31B** of the secondary working load module **30B** is provided with a second current sensor **32B** for sensing the second current. In a preferred embodiment, the first current sensors **52B** and the second current sensor **32B** are current-sensing resistors or power transistors. To maintain a constant current, the weighter **42B** sums the first current values of the first circuits **51B** and the second current value of the second circuit **31B**; outputs the sum to the controller **41B**, where the sum is compared with a preset target current value; and sends a control signal to each variable-impedance controller **50B** as feedback in order for the primary working load module **20B** to be supplied with a constant current.

In this embodiment, the signals obtained from the first current sensors **52B** and the second current sensor **32B** are voltage values. The weighter **42B** sums the voltage values and sends the sum to the negative input of the controller **41B**. The positive input of the controller **41B** is connected to an adjustable constant voltage source **43B**. Based on the electrical potential difference between its positive and negative inputs, the controller **41B** outputs through its output end a control signal for changing the impedance value of each variable-impedance controller **50B**. The voltage value of the adjustable constant voltage source **43B** can be adjusted via the controller **60B** in order to produce the desired lighting mode. In another preferred embodiment, the signals obtained from the current sensors are current values instead; the present invention has no limitation in this regard.

The foregoing configuration is such that, when the operating voltage of the secondary working load module **30B** is changed, the weighting controller **40B** can track the resulting current value changes in real time and modulate the impedance values of the variable-impedance controllers **50B** accordingly so as to keep a constant current through the primary working load module **20B**. In the meantime, the voltage recovered is used to drive the secondary working load module **30B** such that an energy-saving effect is produced.

In summary of the above, the present invention uses a weighting controller and a variable-impedance controller to modulate the divided voltage across a secondary load module so that a constant current through the primary load module is effectively ensured to prevent an otherwise fluctuating voltage or current from shortening the service life of

the LED(s) driven by the driving system. In addition, the invention recovers and reuses the electricity that may otherwise be lost as heat but that is intended for use by the load in the first place; thus, not only is the device to which the driving system is applied protected from an undesirable increase in temperature, but also the power consumed by the entire circuit of the device can be lowered to save energy.

The above is the detailed description of the present invention. However, the above is merely the preferred embodiment of the present invention and cannot be the limitation to the implement scope of the present invention, which means the variation and modification according to the present invention may still fall into the scope of the invention.

What is claimed is:

1. A constant-current-source driving system, comprising:
a power source module;
a primary working load module connected to the power source module in order to be driven by electricity provided by the power source module;
a secondary working load module connected to the primary working load module and parallel-connected to a variable-impedance controller; and
a weighting controller connected to a first circuit of the variable-impedance controller and to a second circuit of the secondary working load module in order to obtain a first current value of the first circuit and a second current value of the second circuit, wherein the weighting controller sums up the first current value and the second current value to obtain a current summation value and compares the current summation value with a preset target current value to accordingly send a control signal to the variable-impedance controller as feedback to increase or decrease the first current value to keep the current summation value approach the preset target current value in order for a constant current to be supplied to the primary working load module.
2. The constant-current-source driving system of claim 1, wherein the weighting controller includes a controller connected to the variable-impedance controller and a weighter connected to the first circuit of the variable-impedance controller and the second circuit of the secondary working

load module; the weighter sums the first current value of the first circuit and the second current value of the second circuit, outputs the sum to the controller, where the sum is compared with a preset target current value, and sends a control signal to each variable-impedance controller as feedback in order for the primary working load module to be supplied with a constant current.

3. The constant-current-source driving system of claim 2, wherein the weighter is connected to a first current sensor provided on the first circuit of the variable-impedance controller to obtain the first current value, and the weighter is connected to a second current sensor provided on the second circuit of the secondary working load module to obtain the second current value.

4. The constant-current-source driving system of claim 3, wherein the first current sensor and the second current sensor are current-sensing resistors or power transistors.

5. The constant-current-source driving system of claim 1, wherein the variable-impedance controller is a field-effect transistor (FET)-based voltage control resistor.

6. The constant-current-source driving system of claim 1, wherein the power source module includes a rectifier connected to mains electricity and an electromagnetic interference filter (EMI filter) connected to a rear end of the rectifier.

7. The constant-current-source driving system of claim 1, wherein the primary working load module includes a plurality of series-connected load units, and a forward-biased diode is provided in parallel between a rear end of each load unit and the secondary working load module.

8. The constant-current-source driving system of claim 7, wherein the forward-biased diode is provided with a switch unit on its front end or rear end, and the switch unit is connected to a controller in order to be turned on or off under the control of the controller.

9. The constant-current-source driving system of claim 7, wherein the load unit is a light-emitting unit or light-emitting array composed of one or a plurality of LEDs.

10. The constant-current-source driving system of claim 1, wherein the secondary working load module is a micro control unit (MCU), a sensor, or a constant-voltage or constant-current driving module.
